UNITED STATES PATENT OFFICE.

GEORGE H. PEGRAM, OF NEW YORK, N. Y.

SUBMERSIBLE BOAT.

1,281,414.

Specification of Letters Patent. Patented Oct. 15, 1918.

Application filed August 16, 1917. Serial No. 186,450.

To all whom it may concern:

Be it known that I, GEORGE H. PEGRAM, a citizen of the United States, and resident of New York city, county of New York, and 5 State of New York, have invented an Improvement in Submersible Boats, of which the following is a specification.

My invention relates to submersible boats or submarines suitable for commercial or 10 other purposes, but more especially adapted to the uses of naval warfare.

It consists essentially of a boat of generally circular or oval shape in plan, having a central compartment of tower form with 15 dome top and, when employed as a war vessel, protected by light armor plate for housing the machinery and guns, surrounded by water-tight compartments to be used for quarters, supplies, auxiliary machinery, storage batteries, torpedo tubes, and also for ballast and, when advisable, full tanks.

The boat is propelled by engines or motors operating, preferably, propellers in duplicate, which move the water through a draft 25 tube in the bottom of the boat, taking it in at the bow and expelling it at the stern, by which the bow wave is reduced and the stern depression lessened, a desirable object as it facilitates motion in a boat of generally circular shape. A central telescopic stack is 30 desirably provided through which air is drawn for the combustion of fuel and mechanical ventilation of the ship; it also serving as an observation tower from which, 35 when desired, the boat may be navigated.

Torpedo tubes of any desired number may be arranged around the circular hull for fire in any direction without necessity of excessive maneuvering of the boat. The outer 40 encircling compartments may, when desired, be filled with water for additional protection.

Submarine boats as now constructed and in use have numerous inherent defects, which 45 it is the object of my invention to overcome. First, they require approximately fifty feet of water in which to submerge on account of their height; and because submergence or elevation at definite depths 50 (when wholly submerged) must be provided by the operation of the diving or elevating rudders hinged on horizontal axes, while the ship is in motion. The boat can only come to rest on the surface or on the bottom, all intermediate retained positions of elevation

necessitating that the submarine be under propulsion. By my invention, I provide a boat of shallow draft, small total height, and provided with vertically acting propellers which, when the boat is nearly submerged, 60 operate to complete the submergence and hold it at any desired depth, with or without forward motion as desired. This feature combined with the small length of the ship would permit it to enter harbors and be 65 maneuvered with facility.

Second, the length of the present submarine is the greatest source of weakness, making it a good target for gunfire for ships, or aeroplanes sailing lengthwise. A very long 70 ship is very slow to maneuver. If rammed, it is destroyed no matter where hit, and a torpedo exploding on one side will open up the seams on the other side, just as a beam is broken by pressure exerted on one side. The 75 general circular boat construction of my invention corrects these faults of length. If hit by a torpedo it could not be broken, and the effect would be to move the whole ship and possibly break open one of the water- 80 filled compartments. It is obvious that the chance of being hit at all is small in comparison to the present submarine, and the curved outer surfaces of my improved boat would tend to deflect the torpedo without 85 exploding it unless it struck end on almost radially of the hull.

Third, the submarines in use are defensively so weak that they must use guns at a great distance and must submerge promptly 90 upon the approach of destroyers. They carry guns of small caliber and usually these require considerable manipulation to get them into action. These defects are overcome by my invention as the boat, when used 95 as a fighting machine has great defensive and offensive strength. The central armored tower may contain in the upper chamber two five-inch guns and the controlling devices of the ship. This chamber is entirely separated from the engine room and has ready access by means of doors to other parts of the boat without going on to the hurricane deck. It is provided with watertight porthole doors which protect the guns 100 from the action of sea-water, at all times when not in action. The propellers and rudders are in duplicate and housed so that they cannot be affected by nets. The boat 105 not only can be run in either direction with 110

equal facility, but may be quickly turned on account of its shape and the action of the propelled water upon the rudder. The ring of torpedo tubes permits quick fire in any 5 direction or all directions and hence may insure protection from simultaneous attacks in all directions.

The general shape of my improved boat makes it comparatively inexpensive, and enables it to be run by a relatively small crew. 10 A large number of these boats distributed over trade lanes would be a most effective protection from present types of submarines, which they could approach or lie in wait for 15 with impunity.

While my improved submersible has special advantages which make it particularly adapted as a war vessel, nevertheless its general construction makes it excellently suitable for use in commerce as a merchant vessel, with or without gun and torpedo defensive protection.

With the above and other objects in view, the nature of which will be more fully understood from the description hereinafter, the invention consists in the novel construction of submersible boats as herein-after more fully described and defined in the claims.

30 For the purpose of illustrating my invention, I have shown in the accompanying drawings the embodiment thereof which is at present preferred by me, since the same is in form to give satisfactory and reliable 35 results, but it is to be understood that the several instrumentalities of which my invention consists, can be variously arranged and organized and that my invention is not limited to the precise arrangement and organization of the instrumentalities herein 40 shown and described.

The construction will be better understood by reference to the accompanying drawings, in which:—Figure 1 is a vertical cross section through the center of the boat 45 on line 1—1 of Fig. 4; Fig. 2 is a cross section across the boat on line 2—2 of Fig. 4; Fig. 3 is a partial vertical cross section on line 3—3 of Fig. 2; and Fig. 4 shows longitudinal half cross sections at different 50 levels on the broken line 4—4 of Fig. 1.

For the sake of clearness, the usual and obvious equipment of a ship or submarine on which no invention is claimed, are omitted 55 from the drawings, such as anchors and chains, boats and davits or skids, derricks, deck hatches, ventilators, doors between compartments, telescopic masts with wireless equipment, periscopes, pumps, air compressors and air tanks, etc.

As before stated, the general shape of the hull is substantially circular in plan and may have its outer bottom walls saucer shaped, as at V, for stability. The top or 65 hurricane deck V' may be curved to slope

down toward the water and thus more effectually deflect a shell which may strike it. Built up from the bottom of the hull is the central tower C', protected by armor and surmounted by the citadel C containing the 70 guns when used as a war vessel; and this tower may have an extensible observation stack W capable of being elevated when necessary.

The hull of the vessel is divided vertically 75 about the tower by a horizontal annular floor C², providing upper and lower compartments. The lower part of the hull below the floor C² is divided into a plurality of ballast and fuel storage compartments D 80 by radial divisions D'. The portion of the vessel above the floor C² is divided circumferentially by a vertical circular wall F² and the inner space is again divided by radial walls F' to form working and storage compartments F. The outer space is likewise divided by radial walls E' into compartments E, which may be used for storage, or when necessary, for water ballast for submergence. They may be also 90 used for containing the torpedo tubes L. The lower part of the tower C' is formed into the engine room B, while the upper portion above the division B' forms the controlling quarters or citadel aforesaid. 95

The vessel at the bottom is provided with a suitable transverse draft tube in which the propellers work, the ends of which are provided with rudders, all of which is described more in detail hereinafter.

The general rounded bottom makes the vessel sea-worthy when awash, and very stable when under gun fire, quickly returning to its normal horizontal balance. I will now proceed to describe the more important 105 details of the construction comprising the more essential requirements of the invention.

A is the water draft tube extending across the bottom of the hull, open at both ends 110 and divided into four or any desired number of parallel tubular compartments under the tower by the vertical division plates or beams b, which support the tower and floor of the engine room, said draft tube 115 terminating in two passages A' at the respective ends and stiffened by the keel webs k and rudder frames r. The compartments A' in which the propellers P are located have no vertical webs. The bottom plate a 120 of the hull is stiffened as required by the ribs b. B is the engine room and contains a pair of explosive or other engines S' of desired type, operating the propeller shafts S, S. C is the clutch by which the propeller shafts and their respective engines may be operated together or singly. M, M, are electric motors operating through the pinions d and d' and spur wheel e to turn the propeller shaft S, the motor being ener- 125 130

gized with current from the usual storage battery, or conversely to be operated by the propeller shaft to charge the batteries when the engines are being used. F^s , F^s , are 5 clutches for disconnecting the pinions d' from the operation of the propeller shaft. T , T , are vertical draft tubes extending through the hull and open at top and bottom for the passage of water upward to 10 submerge the boat, or downward to raise it when submerged through the medium of the propellers Q . These are driven by shafts s and electric motors t , which use electric current from the usual storage battery aforesaid. While screw propellers are 15 shown to move water, it is obvious that other suitable devices may be used to perform the same general function.

When the buoyancy of the ship has been 20 sufficiently overcome by charging the water ballast tanks, the vertical propellers Q act to complete the submergence, and to hold the boat at any depth, whether in motion or not. In case the boat is sunk by sufficient 25 water ballast, the vertical propellers can be used to raise it to near the surface, where the water can be pumped out by the usual pumps against a smaller pressure, thus using less power and requiring smaller pumps.

30 D , D , are water-tight compartments to be filled with water-ballast or fuel oil as desired, of which they have sufficient capacity to take the boat over the cruising range desired. When fuel is pumped from any compartment it may be ballasted with water, if 35 so desired. The fuel compartments may be connected by suitable piping with the oil tank H of the engine room B , from which the engines are directly supplied. I is the 40 drainage tank of the engine room, and which may be automatically pumped out by a suitable air pump i .

45 E , E , are water-tight compartments part or all of which can be filled with water for submergence or for additional protection and stability when in action on the surface. They may be filled by valves e^2 and discharged by pumps e' . F , F , are water-tight compartments with doors f for 50 communication with the engine room, gun room, and with each other, as desired, and are the working and housing quarters of the crew, also containing pumps and compressors, storage batteries, etc. They would also be 55 provided with deck hatches, ventilators, etc., as customary, but not shown.

55 L , L , are torpedo tubes, each closed at its outer ends by a cap h , which is fastened to the hinge pin n , suitably journaled in stuffing-boxes and rigidly connected with the lever O , and also having the studs u for retaining the torpedo T' when the cap is closed. The lever O may be operated by a rod o normally held in place by the catch 60 o' , upon release of which the cap falls by

gravity, and studs u then releasing the torpedo which may be fired by compressed air in the usual way. While I have described the preferred construction of retaining the torpedo in the torpedo tube and for releasing the same when necessary, I make no claim to this construction in this particular application. 70

It is intended that the torpedoes T' will be loaded from the outside and it is not 75 thought necessary to exclude water from the torpedo tubes. The torpedo is discharged by admitting compressed air in the rear, or by any other method. Obviously an additional means would be provided to 80 house and confine the torpedoes when the ship is not in commission or action.

C' is the upper compartment of the tower C and contains the controlling mechanism of the vessel; and when the vessel is used 85 as a war vessel, it constitutes a citadel in which are located the heavy guns g , and also such other lighter guns (not shown) as desired, as well as the controlling mechanism of the vessel. This compartment, when 90 used as a citadel, is inclosed with the armor plate as is also the tower C' , except the necessary gun ports c and any doors which are made hinged and water-tight, so that when submerged the guns will be protected 95 from the action of the sea-water. Two 5-inch guns g are shown in the drawing, and their elevated and depressed positions are indicated in dotted lines. J , J , are 100 girders extending across the tower C' to strengthen it and support the gun carriages G which move along them. When the vessel is to submerge, the guns are withdrawn and the ports closed as at c .

W' is the stack chamber of the tower provided with a suitable water-tight door W^2 , which may be closed tightly when the boat is submerged. W is a telescopic stack having a roof plate w' at its top which makes a water-tight fit with the top of the dome 110 when closed. The several sections of the stack are extended by the use of any of the well known chain pulley devices similar to the manner of operating extension ladders or by other means. Steps or ladders are 115 provided in the sides of the stack sections for men to mount on the top on the inside; and openings w are provided at the top for observation and air entrance. A floor w^2 is also provided upon which the observers may 120 stand when making observations through the openings w .

The boat might obviously be more or less of elliptical or oval form without departing from the essential principles of the general circular design, although for economy of construction and facility of operation the circular form will be generally found desirable. 125

In general, my improved vessel may be 130

used as a fighting machine or as a merchantman, with or without defensive equipment such as guns and torpedo tubes, or both. When employed in commerce for carrying 5 merchandise, part or all of the compartments E may be employed for storage of merchandise. In respect to the means for submerging and propelling the vessel, I do not restrict myself to the precise details de- 10 scribed, nor to the number of draft tubes, conduits or propellers employed, as these details may be varied to suit the special requirements to suit the duty required of the vessel.

15 It will now be apparent that I have devised a novel and useful construction which embodies the features of advantage enumerated as desirable, and while I have in the present instance shown and described the preferred 20 embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

30 1. In a boat of the character stated, a hull of general circular form having a centrally arranged tower portion extending from the bottom to the upper deck, and the annular portion of the hull about the tower portion 35 divided into a plurality of water-tight compartments said tower portion divided by a transverse floor into superimposed compartments, combined with operating machinery in the lower compartment, and ordnance in 40 the upper compartment.

2. In a boat of the character stated, a hull of general circular form and general spheroidal bottom and deck portions, and a tower structure centrally arranged and extending 45 from the bottom to above the deck portion to provide a controlling compartment, the body of the hull having radial division plates extending radially from the tower outward to the sides and bottom.

50 3. In a boat of the character stated, a hull of general circular form and general spheroidal bottom and deck portions, and an armored citadel centrally arranged and extending above the deck portion, the body of 55 the hull having radial division plates extending radially from the citadel outward to the sides and bottom and providing a plurality of water-tight compartments arranged circumferentially about the citadel and an 60 inner chambered portion between the water-tight compartments and the citadel.

4. In a boat of the character stated, a hull of general circular form and general spheroidal bottom and deck portions, an armored 65 citadel centrally arranged and extending

above the deck portion, the body of the hull having radial division plates extending radially from the citadel outward to the sides and bottom, and circumferential division plates forming annularly arranged inner 70 working and storage compartments and outer water-tight compartments, and additional water-tight compartments extending below both the inner and outer compartments first mentioned. 75

5. In a boat of the character stated, a hull of general circular form and general spheroidal bottom and deck portions, an armored citadel centrally arranged and extending above the deck portion, the body of 80 the hull having radial division plates extending radially from the citadel outward to the sides and bottom, circumferential division plates forming annularly arranged inner working and storage compartments 85 and outer water-tight ballast compartments, additional water-tight compartments extending below both the inner and outer compartments first mentioned, and a plurality of torpedo tubes arranged radially about the 90 boat and extending through the outer water-tight compartments and into the inner working and storage compartments. 95

6. In a boat of the character stated, a hull having a central tower portion extending 95 from bottom to upper deck and divided into an upper compartment from which to control the boat and a lower compartment for operating machinery, said hull also having a surrounding series of compartments which 100 when filled with water act as protection to the tower portion, combined with means for supplying water to the compartments.

7. In a boat of the character stated, a hull of generally circular form having a central 105 armored tower and two series of surrounding compartments the inner series of said compartments providing room for auxiliary machinery, crew quarters and supplies and the outer series for water ballast and for 110 protection, the tower also divided into a lower compartment for propelling machinery and an upper compartment for guns, combined with an extensible observation stack centrally arranged at the upper part 115 of the tower.

8. In a boat of the character stated, a hull of generally circular form having a central tower portion extending from the bottom of the hull to and above its deck to provide 120 a citadel at the top for guns and an engine room at the bottom, said hull having water and oil compartments under said tower and around its lower portion.

9. In a boat of the character stated, the 125 hull having a transverse conduit at the bottom and vertical conduits extending from the bottom and arranged at opposite sides of the transverse conduit, combined with propelling means in the transverse conduit, 130

and propelling means in the vertical conduits.

10. In a boat of the character described, a hull of substantially circular form having a plurality of torpedo tubes arranged radially about the hull for fire in substantially all directions in a horizontal plane.

In testimony of which invention, I hereunto set my hand.

GEORGE H. PEGRAM.
